UNITED STATES PATENT OFFICE.

ALLEN A. LYON, OF BELVIDERE, ILLINOIS.

DESIGN FOR A BIRD BATH.

60,912.

Specification for Design. Patented Apr. 25, 1922.

Application filed July 9, 1921. Serial No. 483,571. Term of patent 7 years.

To all whom it may concern:

Be it known that I, ALLEN A. LYON, a citizen of the United States, residing at Belvidere, in the county of Boone and State of Illinois, have invented a new, original, and ornamental Design for a Bird Bath, of which the following is a specification, reference being had to the accompanying drawing, in which a perspective view of the design is shown.

I claim:

The ornamental design for a bird bath, as shown.

In testimony whereof I affix my signature.

ALLEN A. LYON.
